UNITED STATES PATENT OFFICE.

JOHN P. SUNDERLAND, OF ALBANY, NEW YORK, ASSIGNOR, BY DIRECT AND MESNE ASSIGNMENTS, TO GEORGE G. MILNE, OF RYE, NEW YORK.

ELECTRIC HEATING APPARATUS.

1,304,624.

Specification of Letters Patent. Patented May 27, 1919.

Application filed August 1, 1917. Serial No. 183,831.

To all whom it may concern:

Be it known that I, JOHN P. SUNDERLAND, a citizen of the United States, and a resident of Albany, in the county of Albany and State of New York, have invented certain new and useful Improvements in Electric Heating Apparatus, of which the following is a specification.

My invention relates to electrical heating apparatus, and especially to apparatus for heating rivets by passing an electric current therethrough.

The main object of the invention is to provide an apparatus of this character which is not only simple and efficient in operation and construction, but by means of which rivets and the like may be very rapidly heated.

A further object is to provide an apparatus of the general character in question, which may be so operated that the rivets will not be burnt or overheated.

A further object of the invention is to provide an apparatus by which the longer rivets may also be heated very rapidly and without danger of burning or overheating them.

Further objects, features and advantages will more clearly appear from the detail description given below, taken in connection with the accompanying drawings, which form a part of this specification.

In the drawings,

Figure 1 is a side view of an apparatus embodying my improvements in one form;

Fig. 2 is a plan view of the same, certain parts being omitted or broken away to more clearly illustrate others;

Fig. 3 is a front end view of the same, certain parts being omitted to more clearly illustrate others;

Fig. 4 is a section on the line A—A of Fig. 2;

Fig. 5 is a section through the transformer, taken on the line B—B of Fig. 2; and

Fig. 6 is a diagram illustrating diagrammatically the transformer connections and windings.

Referring to the various figures, 1 repre-

sents a base board on which is secured an insulating board or sheet of asbestos 2. Secured upon one end of the base is an electrical contact head of soft metal, such as copper, 3, extending along the front of the apparatus. Pivoted to the framework at 5 are two pairs of arms 4, in the ends of which are secured, respectively, electrical contact heads of soft metal, such as copper, 6, the heads being insulated from the arms 4, which support them. Handles 7 are suitably secured to the arms 4, so that the heads 6 may be raised and lowered away from and toward the head 3 to permit the insertion of rivets 8 between the heads, with one end of each rivet abutting the head 3 and the other end of each rivet abutting one of the heads 6.

9 represents a transformer, suitably secured to the base, and having bolted to the top thereof brackets 10, which may serve as handles for the apparatus. The primary of the transformer consists of three sets of windings 11, 12 and 13, consisting of 100 turns each, of copper wire, wound upon a laminated iron core 14 (see Fig. 5). The secondary windings of the transformer consist of four main turns 15, 16, 17 and 18. Each turn comprises a solid copper bar, bent to make one turn about the core 14. The upper ends of turns 15 and 17 are connected together by copper straps 19, the lower ends of turns 16 and 18 are connected together by copper straps 20, the upper end of turn 16 is connected to the lower end of turn 15 by copper straps 21, and the upper end of turn 18 is connected to the lower end of turn 17 by copper straps 22. Bolted between the straps 19 are two sets of copper strap conductors 23 and 24, one-half of the straps 23 being bolted to the underneath side of one of the heads 6, and the other half of the straps 23 being bolted to the top of the head 6, as clearly indicated in Fig. 1. Likewise, one-half of the straps 24 are bolted to the underneath side of the other head 6, and the other half of the straps 24 are bolted to the upper side of the other head 6, so that each head 6 is electrically connected to the upper ends of turns 15 and 17 through flexible connections. Bolted between the straps 20 are two

sets of flexible electric strap conductors 25 and 26, which are similarly bolted to the lower head 3, half being bolted to the underneath side of said head, and half being 5 bolted thereto on the upper ledge of the head, as clearly indicated in Fig. 1.

I also provide two extra secondary turns on the transformer, these turns being indicated at 27 and 28 (see Fig. 5). The turn 27 10 lies adjacent the turn 15 and is in electric contact therewith substantially over its whole length. The turn 28 lies adjacent the turn 16, but is insulated therefrom by insulating material 29. The upper end of turn 27 15 is electrically connected to the upper end of turn 28 by copper connecting straps 30. The lower end of turn 27 is connected to the lower end of turn 28 by connecting straps 31.

Surrounding the primary and secondary 20 windings is a laminated magnetic structure of soft iron 32, the shape of the laminations being shown in Fig. 5. In this figure, the shape of the laminations of the core structure 14 is also shown.

25 The ends of the primary turns are brought out from the primary coils to a connection box 33.

Pivoted to a cross-bar 34 (see Fig. 2) are 30 two sets of arms 35 and 36. Back of the said arms 35 is a wedge-shaped member 37, and back of the arms 36 is a wedge-shaped member 38, the members 37 and 38 being connected to the upper end of arms 39 and 40, pivoted at 41 (see Fig. 2) and connected 35 to lever arms 43 and 44, respectively, so that, upon depressing the lever arm 43 or 44, the wedge-shaped member connected thereto will be forced between the inner ends of the arm 35 or 36 and cause the outer ends of the 40 pair of arms to approach one another and engage the rivet 8 intermediate its ends, so as to make an electrical contact with the rivet intermediate its ends.

Bolted between the conductive straps 31 is 45 a set of copper connecting straps 45, divided into four groups, the outer end of each group being secured to make electrical connection with the inner end of one of the arms 35 and 36, respectively (see Figs. 1 and 2).

50 Any suitable connections 46 may be made to the ends of the lever arms 43 and 44, so that these arms may be depressed to cause the arms 35 and 36 to electrically engage the rivets therebetween, and likewise any suitable means may be provided to cause the arms 43 and 44 to be retained in their depressed condition, so that the arms 35 and 36 55 will continue to engage their respective rivets during the heating thereof.

60 In operation, the rivets are placed between the heads 3 and 6, and the head 6 lowered thereon so as to hold the rivets therebetween under pressure. In the machine shown, the pressure is about eight pounds.

Assuming the transformer to be energized, 65 current then passes from the secondary terminals through the heads 3 and 6 and through the rivet, causing the rivet to be heated from its flat end down; that is, it becomes hottest at its flat end and the rivet 70 gradually becomes softened from its flat end downwardly or toward its head.

The heating of the rivet is caused by 75 liberation of energy due to the opposition to the current. This opposition may be divided into two classes, that due to the contact resistance between the contact heads and the ends of the rivet which depends upon the softness of the metal of the contact heads and the pressure applied, and 80 that due to the effective impedance in the rivet which may consist of ohmic resistance, hysteresis losses, eddy current losses, inductance and skin effect losses. These vary materially with the shape and size of the 85 rivet and the material from which it is made, and the nature of the current employed. In the apparatus described the contact resistance between the contacts and the ends of the rivet is such that the upper 90 or flat end of the rivet heats faster than the shank or middle portion of the rivet. This appears to be due to a relatively large amount of heat liberated at this end at the point of contact, by the current overcoming 95 the contact resistance. In this manner the heat is concentrated where it is needed most so that the final heating of the rivet is accomplished in a minimum time and with a minimum consumption of energy. 100

However, this is perhaps not the most important feature, because, if the end of the rivet is melted or burned by this so-called concentration of heat, it is not suited to be 105 afterward inserted in the hole in the work because of the damaged end. This burning of the rivet is the local melting or liquefying of the rivet at the end of the rivet adjacent the contact. Burned rivets are thrown away as scrap and even by the old methods 110 of heating by coal or oil flame this loss is very large. I have found however, that by using a relatively low voltage this burning of rivets can be entirely eliminated without material loss in time in completing the heating of the rivets. If an excessive voltage is 115 used, so much heat is generated at the contact that it can not be conducted into the body of the rivet fast enough to prevent local overheating and burning of the rivet 120 at the ends. To prevent burning with the apparatus described I may use an applied voltage of about 2 volts or slightly less. However the highest voltage which will not burn depends not only upon the size, shape and 125 material of the rivet, and nature of the current but also upon the speed with which the contact heads conduct the heat away from

the end of the rivet and the relative value of the contact resistance. I find, however, that according to the preferred form of the invention it is best to use well below six 5 volts.

I find that with the apparatus described the rivet heats up relatively slowly at the head end or rounded end of the rivet. I believe this to be due to the fact that this 10 end of the rivet being rounded tends to bite into the copper head more and form a better electrical connection therewith, so that there is less contact resistance at this head end and hence less generation of heat there 15 due to the contact resistance. I find that some rivets have a small projection in the center of the head end, apparently produced in the forging of the rivet, and that when such rivets are heated according to my 20 method, even less heat seems to be generated by the contact resistance at the head end. Where the head end has a flat surface contacting with the electrical contact head, substantially equal in area to the area of the 25 upper end of the rivet, I find that the generation of heat at the lower end seems to be substantially equal to the generation of heat at the upper end and the rivet is heated from both ends inwardly. It will be 30 understood that by suitable adjustment of conditions the ratio between the effective internal impedance in the rivet and the contact resistances may be such that all 35 parts of the rivet will heat up equally fast or the center will heat up fastest, but the heating of the end fastest has the important advantage that the rivet is heated sufficiently for practical purposes in very much less time and with the consumption of much 40 less energy, considerations which are of great importance, speed being an especially important factor in present day commercial operation. The pressure exerted on the softened end of the rivet by the contact 45 heads is, of course, insufficient to displace the softened metal, as otherwise the rivet could not be inserted in the hole for which it is designed.

If a long rivet is being heated, it is desirable 50 to make use of the third contact device or devices 35 and 36, in which case lever arm 43 is depressed, causing extra current, generated in the secondary turns 27 and 28, to be passed through the upper end portion of 55 the rivet, so as to more quickly heat that portion of the rivet which is desired to be heated and without burning the rivet,—that is, causing it to become too soft at the end that is to be upset later.

60 Suitable switching apparatus is provided, as shown in Fig. 6, whereby the number of turns of primary windings may be varied,—that is, some of the turns may be cut out. For that purpose, a switch 50 is provided,

adapted to make contact with contact 51, if 65 all 300 turns are desired to be in circuit. When the switch is thrown to contact 52, only 275 turns will be in circuit, and when thrown to contact 53, only 200 turns will be in circuit, the supply mains being connected, 70 one to the switch 50 and the other to contact 54.

In the apparatus particularly illustrated in the drawings, I prefer to apply 220 volts at 60 cycles across the primary and to have 75 the transformer so wound that about 3 amperes will flow in the primary when the secondary is open-circuited.

It will be noted that the four main secondary turns are connected in pairs,—two 80 pairs in parallel, and two pairs in series.

When heating rivets $\frac{1}{4}$ inch in diameter by 1 inch long, I preferably use the 300 turns of primary windings, and when so connected the calculated voltage on the secondary with 85 the secondary open-circuited is about 1.4 volts.

With rivets $\frac{3}{8}$ inch diameter by $1\frac{1}{2}$ inches long, I preferably cut out part of the primary turns, so as to use only 275 primary 90 turns, thus producing a calculated open-circuit secondary voltage of about 1.6 volts.

When heating rivets $\frac{1}{2}$ inch diameter by $2\frac{1}{2}$ inches long, I preferably use about 200 turns in the primary and a calculated open-cir- 95 circuit secondary voltage of about 2 volts.

If a $\frac{3}{8}$ inch diameter by 3 inches long rivet is being heated, I preferably increase the open-circuit secondary voltage to about 2.5 volts, and if a $\frac{5}{8}$ inch diameter by $4\frac{1}{4}$ 100 inches long rivet is being heated, I preferably increase the calculated secondary voltage to about 3.5 volts.

If, however, a voltage materially higher than the above values is used in the above 105 described machine shown in the drawings, I find that the rivets are apt to be burnt. On the other hand, it is desirable to use as great a voltage as is advantageous, in order that the rivets may be heated as quickly as possible.

I find that the smaller size rivets may be heated more quickly and without burning by applying a voltage of about 2 volts (actual voltage applied with heating current flowing) if proper conditions of contact, etc., are maintained. The voltage applied when the heating current is flowing I find to be about .3 or .4 volt lower than the calculated open circuit voltage in the above described appa- 110 ratus.

When long rivets are used, such as $2\frac{1}{2}$ inches or over, I preferably make use of the third contact devices 35 and 36, so that the additional current is sent through the rivet 125 to cause it to be heated and softened down to the desired extent more rapidly and without burning the rivet.

With the above apparatus, I am enabled to heat rivets in from 3 to 60 seconds without burning.

To prevent burning, I preferably keep the open-circuit secondary voltage to about 2 volts. In any event, I believe the open-circuit secondary voltage should be less than 6 volts. Thus, the transformer should be so designed and wound or the source of electric current be so selected and connected as to send a current through the heads and rivet of such size as to heat the rivet soft the required distance without burning the end of the rivet.

15 While I prefer to use alternating current as energizing means, certain of my improvements may be found advantageous in case a direct current is used.

At the ends of the core 14, I provide air spaces 60 filled with shellac, so that, in case the secondary should become short-circuited, flow of excessive secondary current will be prevented.

It is not necessary, to the broader aspects 25 of my invention, that the apparatus be provided with two heads 6, but I find that if a plurality of heads 6, with coöperating head or heads 3, is provided, supplied from the same source or transformer if desired, and 30 in parallel if desired, a plurality of rivets may be heated simultaneously. I find that, even although such plurality of rivets may be inserted simultaneously, one will always become heated before the other, so that the 35 operator may insert and remove the rivets alternately, and thus greatly increase the speed with which rivets may be heated by the apparatus.

As shown in the drawings, only one head 40 3 is provided, but this is equivalent to two heads, as one portion coöperates with one head 6 and the other portion coöperates with the other head 6.

Since the third contact device 35 is connected to secondary windings on the transformer, which embrace only two turns in parallel, the voltage applied between the contact devices 35 and 36 and the head 6 will be about half of the voltage applied 50 between the heads 6 and 3.

It will be noted that the other or upper terminal of the secondary windings 27 and 28 are common with the upper terminal of the winding 15 and connections 23.

55 While I have described my improvements in great detail in respect to an apparatus embodying them in one form, I do not desire to be limited to such details, since many changes and modifications may be made 60 without departing from the spirit and scope of the invention in its broader aspects. I desire to cover all forms of apparatus coming within the language of the appended claims.

What I claim is:

65 1. An apparatus of the class described

having in combination a transformer with its primary and secondary, a plurality of contact heads connected to one terminal of the secondary and a single or common contact head connected with the other terminal 70 of the secondary and adapted to coöperate with each of the first mentioned contact heads to conduct current through the work placed between said contact heads respectively.

2. An apparatus of the class described having in combination a transformer with its primary and secondary, a plurality of contact heads connected to one terminal of the secondary and a single or common contact head connected with the other terminal of the secondary and adapted to coöperate with each of the first mentioned contact heads to conduct current through the work placed between said contact heads respectively, and means for independently moving the first mentioned contact heads toward and away from said common head.

3. An apparatus of the class described having in combination a transformer with its primary and secondary, a plurality of contact means, flexible conducting straps connecting said means with one terminal of the secondary and in parallel with one another, contact means forming an electrode 90 means opposing said first contact means and electrically connected to the other terminal of the secondary, and means for independently moving said first contact means substantially for the purpose described.

4. An apparatus of the class described having in combination a transformer with its primary and secondary, a plurality of contact heads, flexible conducting straps connecting said heads with one terminal of the secondary, a stationary contact forming an electrode means opposing said contact heads and electrically connected to the other terminal of the secondary, and means for independently moving said contact heads substantially for the purpose described.

5. In an electric rivet heating apparatus, the combination of a transformer, a plurality of pairs of electrical contact heads between each pair of which a rivet is adapted 115 to be placed with one of its ends abutting one head of the pair and its other end abutting against the other head of the pair, and connections from said heads to said transformer and means for moving the heads of one pair toward one another independently of the heads of another pair.

6. In an electric rivet heating apparatus, the combination of a plurality of pairs of electrical contact heads between each pair of which a rivet is adapted to be placed with one of its ends abutting one head of the pair and the other of its ends abutting the other head of the pair, said heads having substantially flat faces where they abut the 125 130

rivets, a source of electric current, and connections from said heads to said source and means for moving the heads of one pair toward one another independently of the 5 heads of another pair.

7. In an electric rivet heating apparatus or the like, the combination of a plurality of pairs of electrical contact means between each pair of which a rivet or the like is 10 adapted to be placed with one of its ends abutting one contact of the pair and another part of the rivet or the like being connected to the other contact means of the pair, a source of electric current, and connections from said contact means to said source, one contact means of each pair being 15 movable away from and toward the other contact means of the pair to permit insertion of the rivet or the like between the contact means of the pair independently of the contact means of another pair.

8. An apparatus of the class described having in combination two opposing contact heads adapted to contact with the ends 25 of a rivet respectively, said heads having substantially flat faces where they make contact with the rivet and being of relatively soft metal whereby the contact resistance with the head of the rivet is relatively low, 30 and a source of electric current connected to said contact heads.

9. An apparatus of the class described having in combination a transformer with its primary and secondary, a plurality of 35 contact heads, flexible conducting straps connecting said heads with one terminal of the secondary, contact means forming an electrode means opposing said contact heads and electrically connected to the other terminal 40 of the secondary whereby a plurality of rivets or the like placed between said contact heads and means respectively will be simultaneously energized in parallel from said secondary.

45 10. An apparatus of the class described having in combination two opposing contact heads adapted to contact with the ends of a rivet respectively, said heads having substantially flat faces where they make contact with the rivet and being of relatively soft metal whereby the contact resistance with the head of the rivet is relatively low, 50 a source of electric current connected to said contact heads, and means causing the contact heads to engage the rivet with a predetermined pressure.

55 11. An apparatus of the class described having in combination two opposing contact heads adapted to contact with the ends of a rivet respectively, said heads having substantially flat faces where they make contact with the rivet, means causing the contact heads to engage the rivet with a predetermined pressure and incapable of displacing 60 the heated metal of the rivet, and a source of

electric current connected to said contact heads.

12. In an electric rivet heater or the like the combination of a contact head having a substantially flat face adapted to contact 70 with the flat end of the rivet or the like, contact means making contact with the other part of the rivet with less contact resistance, means causing the contact head to engage the rivet with a predetermined pressure and 75 incapable of displacing the heated metal of the rivet, and a source of electric current connected to said contact head and contact means for the purpose described.

13. In an electric rivet heating apparatus or the like, the combination of means for sending current through the rivet or the like from end to end and means for sending additional current through one end portion of 80 the rivet or the like.

14. In an electric rivet heating apparatus, the combination of two electrical contact heads between which the rivet is adapted to be placed with one end of the rivet contacting with one head and the other end of the 90 rivet contacting with the other head, and an electrical contact device adapted to contact with the rivet intermediate its ends.

15. In an electric rivet heating apparatus or the like, the combination of two electrical contact means between which the rivet is adapted to be placed with one end of the rivet or the like contacting with one means and the other end of the rivet or the like contacting with the other means, an electrical contact device adapted to contact with the rivet or the like intermediate its ends, and means applying a potential difference between said contact means, and means connecting said electrical contact device with a 100 source of electrical energy to apply a less difference of potential to the rivet or the like between one of the contact means and said electrical contact device.

16. In an electric rivet heater the combination of a contact head having a substantially flat face adapted to contact with the small end of the rivet, contact means making contact with the other end of the rivet, means causing the contact head to engage the rivet with a predetermined pressure and incapable of displacing the heated metal of the rivet, and a source of electric current connected to said contact head and contact means for the purpose described.

17. In an electric rivet heating apparatus, the combination of two electrical contact heads between which the rivet is adapted to be placed with one end of the rivet contacting with one head and the other end of the 115 rivet contacting with the other head, an electrical contact device adapted to contact with the rivet intermediate its ends, and means for moving said electrical contact device into and out of contact with the rivet.

6

18. In an electric rivet heating apparatus, the combination of two electrical contact heads between which the rivet is adapted to be placed with one end of the rivet contacting with one head and the other end of the rivet contacting with the other head, one of said heads being movable with respect to the other head, a transformer having its secondary connected to said heads, an electrical contact device adapted to contact with the rivet intermediate its ends, and means for moving said electrical contact device into and out of contact with the rivet.

19. In an electric rivet heater or the like the combination of a contact head having a substantially flat face of relatively soft metal, adapted to contact with the flat end of the rivet or the like, contact means making contact with the other part of the rivet,

means causing the contact head to engage 20 the rivet with a predetermined pressure and incapable of displacing the heated metal of rivet, and a source of electric current connected to said contact head and contact means for the purpose described. 25

20. In an electric heating apparatus of the class described, the combination of two electrical contacts and means connected thereto adapted to send a current through the article to be heated and a third contact with means 30 connected thereto adapted to increase the current through a part of the article to be heated.

Signed at New York in the county of New York and State of New York this 30th day 35 of July A. D. 1917.

JOHN P. SUNDERLAND.

Correction in Letters Patent No. 1,304,624.

It is hereby certified that in Letters Patent No. 1,304,624, granted May 27, 1919, upon the application of John P. Sunderland, of Albany, New York, for an improvement in "Electric Heating Apparatus," an error appears in the printed specification requiring correction as follows: Page 5, line 96, claim 15, after the word "rivet" insert the words *or the like*; and that the said Letters Patent should be read with this correction therein that the same may conform to the record of the case in the Patent Office.

Signed and sealed this 8th day of July, A. D., 1919.

[SEAL.]

Cl. 219—11.

R. F. WHITEHEAD,
Acting Commissioner of Patents.
